UNITED STATES PATENT OFFICE.

RICHARD T. CRANE, OF CHICAGO, ILLINOIS.

DESIGN FOR A FLANGE-UNION.

SPECIFICATION forming part of Design No. 16,160, dated July 14, 1885.

Application filed May 15, 1885. Term of patent 14 years.

To all whom it may concern:

Be it known that I, RICHARD T. CRANE, a citizen of the United States, residing at Chicago, in the county of Cook and State of Illinois, have invented and produced a new and original Design for Flange-Unions, of which the following is a specification, reference being had to the accompanying drawings, in which—

Figure 1 is a plan view of my newly-designed flange-union, and Fig. 2 a transverse sectional view of the same, these two figures being deemed necessary to fully illustrate my design.

Heretofore flange-unions have been made the bodies of which presented the appearance of a circular disk of considerable thickness, or, in other words, of the section of a cylinder, with radial lugs extending outwardly from the periphery of the body.

My design consists in a flange-union composed of a body having a raised central portion and a lower outer portion surrounding the same, both circular in form, but of different diameters, and radially-projecting lugs extending outward from the central portion of the body, as hereinafter described.

In the drawings, A represents the raised central portion of the body, which is circular in its form, as shown, and B the outer portion,

which is also circular in general outline, and is of a greater diameter than the central portion, A, and of less height, as shown. C represents four lugs, which project radially from the central portion, A, of the body and extend outward beyond the periphery of the outer portion, B, the said lugs being of a less height than the central portion, but rising somewhat above the upper surface of the outer portion, as shown, and being arranged at distances of ninety degrees apart. The surface at the junction of the two portions of the body and of the lugs is preferably rounded off, as shown, to present a more pleasing and tasteful appearance.

Having thus described my design, what I claim as new, and desire to secure by Letters Patent, is—

The design for a flange-union herein shown and described, the same consisting of the body having the raised central portion, A, and lower outer portion, B, both circular in form, but of different diameters, and the radially-projecting lugs C.

RICHARD T. CRANE.
